AQUATIC GAME SPEEDWAY

Harold N. Braunhut, % Honey Toy Industries, Inc.,
200 5th Ave., New York, N.Y. 10010

Filed May 22, 1974, Ser. No. 472,288

Term of patent 14 years

Int. Cl. D21—01

U.S. Cl. D34—5 CC

FIG. 1

FIG. 2

FIG. 4

FIG. 3

FIG. 5

FIG. 9

FIG. 8

FIG. 7

FIG. 6

FIG. 1 is a top plan view of an aquatic game speedway, showing my new design;

FIG. 2 is a front elevational view thereof;

FIG. 3 is a right-side elevational view thereof, the left side elevational view being a mirror image thereto;

FIG. 4 is a rear elevational view thereof;

FIG. 5 is a bottom plan view thereof;

FIG. 6 is a cross-sectional view thereof, taken along line 6-6 in FIG. 1;

FIG. 7 is a cross-sectional view thereof, taken along line 7-7 of FIG. 1;

FIG. 8 is a cross-sectional view thereof, taken along line 8-8 of FIG. 1; and

FIG. 9 is a cross-sectional view thereof, taken along line 9-9 of FIG. 1.

I claim:

The ornamental design for an aquatic game speedway, substantially as shown.
